UNITED STATES PATENT OFFICE.

FRANK T. COPE, OF SALEM, OHIO, ASSIGNOR TO THE ELECTRIC FURNACE COMPANY, OF SALEM, OHIO, A CORPORATION OF OHIO.

ROTARY FURNACE.

Application filed December 21, 1925. Serial No. 76,676.

The invention relates to continuous furnaces for heat treating articles of various size and shape and more particularly to a furnace of this kind provided with a movable hearth for carrying articles to be treated, the improvement being best adapted to a continuous furnace of the rotary type.

The object of the present improvement is to provide a movable hearth suspended within the furnace from a movable support; a further object being to suspend hooks from the movable support for the attachment of small gears or similar articles above the hearth, whereby the capacity of the furnace may be increased.

An embodiment of the invention is illustrated in the accompanying drawings, in which—

Figure 1 is a side elevation of the improved furnace, one-half being shown in vertical section;

Fig. 2, a plan sectional view of the same, and

Fig. 3, a section substantially on the line 25 3—3, Fig. 2.

Similar numerals indicate corresponding parts throughout the drawing.

The furnace illustrated and described in the present application is of the rotary type 30 although it is obvious that the improvements are adaptable to any form of continuous furnace in which it may be necessary or desirable to provide a moving hearth.

The furnace comprises the annular base or bottom wall 1 and the concentric, cylindrical outer and inner walls 2 and 3, respectively, all of said walls being lined with suitable refractory material shown at 4.

The bottom wall is provided with an annular trough 5 in which may be located electric resistance elements 6 and similar resistors 7 may be mounted upon the side walls of the annular heating chamber.

The top wall of the furnace, indicated at 8, is also lined with refractory material 9 and provided with an annular slot 10 which may be reinforced by the flanges 11 of the metal top plates 12.

The post 13 is centrally located within the furnace structure and has the hub or sleeve 14 journaled upon the upper portion thereof and held against end movement upon the post as by the collar 15 and cap 16.

Radial arms 17, upon the hub 14, carry

a ring 18 located above the annular slot 10 in the furnace roof and a gear 19 is fixed upon the upper end portion of the hub, the inclined brace rods 20 connecting said gear with the ring 18.

This gear meshes with a pinion 21 mounted upon a vertical shaft 22, journaled in any suitable manner in the superstructure 23 of the furnace. This shaft may be driven from any suitable source of power and as illustrated in the drawings may carry the worm gear 24 which meshes with a worm 25 upon a shaft 26. A gear 27 may be fixed upon the shaft 26 and meshes with a pinion 28 upon a drive shaft, whereby the ring 18 may be rotated slowly, either continuously or intermittently.

The ring 18 is thus carried by the hub 14 and arranged to be rotated above the annular slot 10 at the desired speed.

Rods 29 are suspended, at spaced intervals, from the ring 18, being located through the annular slot 10 in the roof of the furnace.

The hearth, which may be in the form of 80 arcuate plates 30, is suspended upon the lower ends of these rods and located within the annular trough 5 in the bottom of the furnace. These hearth plates are preferably detachably suspended upon the rods 29 and as 85 shown each rod may have a block 31 at its lower end provided with studs 32 upon its upper face, said studs being arranged to enter apertures 33 in the end portions of the plates, which rest upon the blocks.

The inner side edge of each hearth plate may be provided with an upright flange 34 to prevent articles placed thereon from being accidentally pushed over the edge of the hearth and down-turned flanges 35 may 95 be provided at each side edge of the hearth plates to strengthen the same and prevent warping or twisting under high temperatures.

A door sill plate 36 may be located at the 100 bottom of the charging door of the furnace, and provided with the down-turned inner edge 37 extended over the periphery of the hearth plates.

Any articles of irregular shape or size may 105 be placed upon the hearth plates for treatment and in order to increase the capacity of the furnace, as well as to heat articles whose treatment is very particular, since articles suspended in the furnace receive heat 110

from all sides and are thus very uniformly heated, hooks 38 may be suspended from the ring 18, between the rods 29, to receive small gears or similar parts as illustrated in Fig. 5 of the drawings.

A charging door 39 is provided in the outer side wall of the furnace through which articles to be treated are placed upon the hearth, which rotates in the direction of the arrow shown in Fig. 2, and a similar discharge door 40 may be located adjacent thereto.

A transverse or radial partition wall 41 is located between the charge and discharge doors and provided with a central slot 42 of sufficient width to permit the rods 29 and hooks 38, to pass therethrough. To prevent damage to the partition walls, in case the operator does not remove the articles, the walls may be hinged so as to swing when any articles are moved against them.

If desired an auxiliary discharge door 43 may be located at a point spaced from the main discharge door 40 in order that articles may be removed from the furnace before the hearth has completed a revolution or to assist in quickly discharging the treated articles from the furnace, or to remove articles which are suspended from the hooks, leaving the hearth to be discharged through the door 40.

I claim:

1. A furnace having a slot in its roof, a supporting member movable along said slot, rods suspended from the supporting member through said slot, and a hearth suspended upon said rods.

2. A furnace including a heating chamber, a movable supporting member, a hearth suspended from said supporting member and arranged to be moved through the heating chamber and article supporting hooks suspended from said supporting member and arranged to support articles spaced above the hearth.

3. A furnace having a slot in its roof, a supporting member movable along said slot,

rods suspended from the supporting member through said slot, a hearth suspended upon said rods and article supporting hooks suspended from said supporting member between said rods.

4. A furnace having an annular slot in its roof, a rotatable ring above said slot, rods suspended from the ring through said slot, and a hearth suspended upon said rods.

5. A furnace having an annular slot in its roof, a rotatable ring above said slot, rods suspended from the ring through said slot, and a hearth comprising plates suspended upon said rods.

6. A furnace having an annular slot in its roof, a rotatable ring above said slot, rods suspended from the ring through said slot, a hearth suspended upon said rods and article supporting hooks suspended from the ring between said rods.

7. A furnace having a slot in its roof, a supporting member movable along said slot, sealing means to prevent loss of heat through the slot, and a hearth suspended from the supporting member.

8. A furnace having a slot in its roof, a supporting member movable along said slot, sealing means to prevent loss of heat through the slot, a hearth suspended from the supporting member, and article supporting hooks suspended from the supporting member above the hearth.

9. A furnace having a circular slot in its roof, a heat insulated ring rotatable above the slot, sealing means to prevent loss of heat through the slot, and a hearth suspended from said ring.

10. A furnace having a slot in its roof, supporting means movable along the slot, gas sealing and heat insulating means carried by the supporting means, and article supporting means suspended from the supporting means.

In testimony that I claim the above, I have hereunto subscribed my name.

FRANK T. COPE.
